UNITED STATES PATENT OFFICE

2,075,061

COMBINED WATER CLOSET AND BIDET

Ippolito Salvoni, New York, N. Y., assignor of forty-four per cent to Riccardo Salmona and twelve per cent to Edward Q. Jackson, both of New York, N. Y.

Application May 23, 1935, Serial No. 23,073

7 Claims. (Cl. 4-7)

This invention relates to sanitary appliances and more particularly refers to improvements in combined water closets and bidets.

In a co-pending application for patent entitled "Combined toilet and bidet", Serial No. 6,062 now Patent 2,036,934, I have described and claimed a bidet adapted to be used in combination with an ordinary water closet, the principal characteristic of said bidet being that it is so designed 5 that it affords ample room for the performance of the service for which it is intended.

To this end, the bidet is formed with a front portion preferably extending beyond the closet bowl and is also preferably wide enough to provide 15 a generous amount of room, enabling the user to efficiently bathe the exposed part of the body.

However, when the bidet is used on top of the seat, in order to provide sufficient depth for its 20 front portion permitting the hand to be inserted in place without difficulty, it is necessary to have the top of the bidet well above the level of the seat so that in some instances the height of the bidet from the floor may cause some discomfort 25 to the user.

In another co-pending application for patent entitled "Bidet attachment for water closets", Serial No. 12,239 now Patent 2,036,935, I have described and claimed an improved arrangement 30 of bidet and toilet seat, whereby the said seat and bidet may be raised or lowered in position without interfering with each other. The seat forming part of said arrangement is open at the front end so that the forwardly extending portion 35 of the bidet can project within the opening of the seat down to the top of the toilet bowl, the result being that the bidet can be made to extend to a lower level above the level of the seat than if a seat of the closed front end type were used.

40 However, I have found that there are instances in practice where it is desirable for the top of the bidet to be at a still lower level than is made possible by the use of an open front end seat in connection with an ordinary toilet bowl. It is of course understood that the level of the top of bidet over the level of the top of the toilet bowl is determined by the necessity of providing sufficient depth at the front end of the bidet for the free insertion of the user's hand. In order to meet this 45 condition, it is therefore necessary for the top of the bidet to remain at a level which is sufficiently above the level of the ordinary toilet seat to make it inconvenient for children and short persons to use it with proper comfort.

50 I have therefore devised the arrangement

forming the object of the present invention, the primary object of which is to provide in a combined water closet and bidet, a novel and improved type of closet bowl making it possible to reduce to a minimum the height which the bidet must reach above the level of the seat, without losing the advantages pertaining to the arrangement described in my second application above referred to.

Another object of the invention is to provide a 10 novel and improved combined water closet and bidet, including a seat of the open front type, in which the closet bowl is formed at the front end with a depression registering with the opening at the front end of the seat, making it possible for 15 the front portion of the bidet to project downwardly to a level materially lower than that of the top of the closet bowl.

A further object is to provide a novel and improved construction of combined water closet and 20 bidet, making it possible for the contour of the bidet itself to follow a relatively smooth curve free of sharply depressed portions, and therefore easier and less expensive to produce and more pleasing to the eye.

Other objects and advantages of my invention 25 will more fully appear as the description proceeds and will be set forth and claimed in the appended claims.

My invention is illustrated by way of example 30 in the accompanying drawings in which:

Fig. 1 is a plan view of my improved water 35 closet and bidet showing the bidet in its lowered position;

Fig. 2 is a fragmentary front view in elevation 35 thereof;

Fig. 3 is a fragmentary longitudinal vertical section through line 3-3 of Fig. 1;

Fig. 4 is a fragmentary vertical section through 40 line 4-4 of Fig. 1;

Fig. 5 is a fragmentary vertical section through line 5-5 of Fig. 1;

Fig. 6 is a fragmentary longitudinal vertical section in an enlarged scale through the spray and discharge system of the bidet;

Fig. 7 is a fragmentary vertical section through line 7-7 of Fig. 6;

Fig. 8 is a fragmentary horizontal section through line 8-8 of Fig. 6;

Fig. 9 is a fragmentary vertical longitudinal 50 section in an enlarged scale showing the valve control system for the admission to and discharge of water from the bidet;

Fig. 10 is a fragmentary horizontal section through line 10-10 of Fig. 9;

Fig. 11 is a fragmentary horizontal section through line 11—11 of Fig. 9;

Fig. 12 is a fragmentary vertical section through line 12—12 of Fig. 10; and

5 Fig. 13 is a fragmentary vertical longitudinal section of a combined water closet and bidet embodying an alternative form of my invention.

Referring to Figs. 1, 2, 3, of the drawings, 20 10 designates a toilet bowl made integral with the usual rearwardly extending portion 21 and having a curved depression 22 at the front end adapted to receive the front portion 23 of the bidet 24.

Said bidet consists of a basin-like structure 15 which is pivotally mounted at the rear and can be moved from the position on top of toilet seat 25, as shown in full lines in Fig. 3, to the position 24' shown in dot and dash lines in the same figure.

20 As stated before, the seat is of the open front end type, and opening 26 at the front thereof remains directly above depression 22 so as to permit front extension 23 of the bidet to project therewithin.

25 By virtue of this arrangement it is possible to make the bidet sufficiently deep for efficient use and yet cause its outwardly extending flange portion 27 to remain but slightly above the level of the seat. As customary the seat is preferably 30 provided with rubber cushioning buttons 28, and in a similar manner the underside of the flange portion of the bidet is provided with rubber cushioning buttons 29.

The bidet is preferably pivotally mounted 35 coaxially with the seat, although pivotal supports on different axes can be used if desired.

By referring more especially to Fig. 3, it will be seen that the fact that the closet bowl is formed with a depression at the front permits an easier merging of the curved bottom of the 40 front portion of the bidet with the curved bottom of the body portion thereof than would otherwise be possible without making the body portion of bidet of an undesirably shallow depth.

45 The structure illustrated in the drawings differs from those shown in the drawings pertaining to my other copending application above referred to in several other respects.

A novel feature of the arrangement shown 50 resides in the manner of supplying water to the bidet. As shown in Figs. 1 to 5, the seat, the bidet and the cover 30 for the bidet are pivotally mounted on the same axis and can be moved up and down independently of one another.

55 A common support for these three parts is provided by elongated plate member 31 mounted at the rear across the bowl extension 21, said plate member being shown provided with a slot 32 through which can be inserted the head of 60 the bolts securing said plate member in position onto the bowl. At each end said plate member is formed with two upwardly extending coaxial supports 33, 34, open at their inner end, in which is rotatably mounted a tubular member 35.

Said supports are each provided with a rearwardly and upwardly extending elbow portion such as shown at 36, 37, forming inlets such as 38 to which cold and hot water supply pipes 39, 70 40, can be connected.

In correspondence of each one of said inlets tubular member 35 is provided with an opening such as 41, which registers with its respective inlet when the bidet is in its lowered position 75 ready for use and which is out of register when

the bidet is moved to its raised position. The bidet is provided with a rearwardly extending hollow bracket 42 having sleeve portion 43 firmly secured onto the central portion of tubular member 35, so that said tubular member shares the angular displacements of the bidet. Said tubular member is provided with an opening establishing a connection for the passage of liquid from the tubular member to the inside of the bracket.

10 As a result the tubular member 35 acts as a cock to admit or cut off the supply of water to the bidet, respectively, when said bidet is lowered in operative position or raised therefrom. In order to prevent leakages, the ends of tubular member 35 are preferably mounted within their respective supports through the intermediary of a stuffing box arrangement constituted by nut 44 and packing 45. In addition to this, the water supply pipes are controlled by valves such as 46, 47, which are preferably placed within easy reach of the user.

Water can be discharged into the bidet either through two discharge outlets located near the top of the bidet at the rear as shown at 48 in 25 Figs. 10, 12, or else through a nozzle 49 upwardly extending from the bottom of the bidet, said nozzle being adapted to direct a jet of water against the exposed portion of the user's body.

Suitable selective means are provided for supplying the water so as to fill the bidet or to issue from nozzle 49. By way of example in the drawings I show a multiple-way valve interposed between tubular member 35 and the bidet, the body 50 of said valve forming part of bracket 42.

30 Said valve also includes a cock 51 rotatably mounted within the valve chamber 52, said cock being formed with an annular chamber 53 provided with two ports 54, 55, arranged at right angles to each other on the same plane and 40 adapted to register with passage 56 connecting chamber 52 with tubular member 35.

Cock 51 is also provided with diametrically opposite ports 57, 58, adapted to establish communication between annular chamber 53 and tubular member 59 when the cock is in the position shown in Figs. 9, 10, 11, and adapted to establish communication between said annular chamber and passages 60, 61, leading to outlets 48 when the cock is displaced 90 degrees in a clockwise direction with respect to Figs. 10, 11.

55 Tubular member 59, which is preferably concealed by a shield 62, runs under the bidet to a point where it can be connected to the elbow portion 63, by means of which the nozzle 49 is secured onto the bottom of the bidet. It will be observed that outlets 48 of the passages 60, 61, lead to the inside of the bidet through offset portions such as shown at 64, which form with the body of the bidet an opening 65 acting as an overflow.

60 After use the water is discharged from the bidet through bottom openings 66 arranged in circumferential series around nozzle 49, said openings leading to an underlying chamber 67 formed by a casing 68, the bottom of which is provided with discharge openings 69. Said openings 69 are controlled by a rotatable valve member 70 pivotally mounted at 71, said valve member being provided with corresponding openings 72 adapted to register with openings 69 when the valve is in the discharging position, said openings 69 being blocked by the solid portions of the valve intervening between adjoining openings 72 when the valve is 75

turned 45 degrees from the position shown in Figs. 6, 8.

The valve may be operated by means of a control lever 73 having a stem 74 running through the core 75 of cock 51. At its lower end stem 74 is provided with a pulley 76 or some other suitable means for connecting a cable 77 which runs within shield 62 and around valve member 70 with which it is in positive engagement as shown at 10 78 in Fig. 8. It is thus seen that by swinging lever 73 to one or the other of two extreme positions, valve 70 can be set in open or closed position at will.

Although I prefer to make the bidet in the form shown in Figs. 1 and 3, where its front portion projects beyond the closet bowl, it is within the scope of my invention to have the front of the bidet extend about as far as the closet bowl and no more if desired, as shown at 79 in Fig. 13; this 20 manner of construction being preferable in such cases where there are space limitations that would interfere with the use of the longer type of bidet.

The constructional details of my invention may 25 vary from those shown without involving any material departure from the inventive idea. The drawings should, therefore, be understood as being intended for illustrative purposes only and not in a limiting sense.

30 I accordingly reserve the right to carry my invention into practice in all those ways and manners which may enter fairly into the scope of the appended claims.

I claim:

35 1. As a new article of manufacture, a water closet bowl comprising a basin like structure having the upper part of its front wall portion cut off to form a depression centrally located with respect to the longitudinal axis of said bowl.

40 2. A combined water closet and bidet comprising a water closet bowl having the upper part of its front wall portion cut off to form a depression centrally located with respect to the longitudinal axis of said bowl, and a bidet supported on top of said bowl, having a front portion downwardly extending within the depression at the front end of said bowl, said bidet being pivotally mounted onto said bowl.

45 3. A combined water closet and bidet comprising a water closet bowl having the upper part of its front wall portion cut off to form a depression centrally located with respect to the longitudinal axis of said bowl, a seat resting on top of said bowl, having an open front end forming a gap in correspondence of said depression, and a bidet supported on top of said seat, having a front portion downwardly extending through said gap and within said depression, said seat and bidet being

pivotaly mounted onto said bowl, and being tilt-able to operative or inoperative position inde- 5 pendently of each other.

4. A combined water closet and bidet comprising a water closet bowl having the upper part of its front wall portion cut off to form a depression centrally located with respect to the longitudinal axis of said bowl, a seat resting on top of said bowl, having an open front end forming a gap in correspondence of said depression, and a bidet supported on top of said seat, having a front portion downwardly extending through said gap and within said depression, said seat and bidet being pivotally mounted onto said bowl, and being tilt-able to operative or inoperative position 10 15 independently of each other, said front portion extending frontwardly beyond said front end.

5. A combined water closet and bidet comprising a water closet bowl having the upper part of its front wall portion cut off to form a depression centrally located with respect to the longitudinal axis of said bowl, a seat resting on top of said bowl, having an open front end forming a gap in correspondence of said depression, a bidet supported on top of said seat, having a front portion 20 25 downwardly extending through said gap and within said depression, and a cover for said bidet, said seat, bidet and cover being pivotally mounted onto said bowl, and being tilt-able to operative or inoperative position independently of one an- 30 other.

6. A combined water closet and bidet comprising a water closet bowl having the upper part of its front wall portion cut off to form a depression centrally located with respect to the longitudinal axis of said bowl, a seat resting on top of said bowl, having an open front end forming a gap in correspondence of said depression, a bidet supported on top of said seat, having a front portion downwardly extending through said gap and within said depression, and a cover for said bidet, said seat, bidet and cover being pivotally mounted onto said bowl, and being tilt-able to 35 40 45 operative or inoperative position independently of one another, the front portion of said bidet and cover extending frontwardly beyond the front end of said bowl.

7. A combined water closet and bidet comprising a water closet bowl having the upper part of its front wall portion cut off to form a depression centrally located with respect to the longitudinal axis of said bowl, a bidet supported on top of said bowl, having a front portion downwardly extending within the depression at the front end of said bowl, and a cover for said bidet, said bidet and cover being pivotally mounted onto said bowl, and being tilt-able to operative or inoperative position 50 55 independently of each other.

IPPOLITO SALVONI.
